(57) **CLAIM**

The ornamental design of a popping toy as shown and described.

DESCRIPTION

FIG. 1 is a front, top perspective view of a popping toy in accordance with the present invention;

FIG. 2 is a top view thereof;

FIG. 3 is a bottom view thereof;

FIG. 4 is a front view thereof;

FIG. 5 is a back view thereof;

FIG. 6 is a left view thereof;

FIG. 7 is a right view thereof;

FIG. 8 is a front, top perspective view of another embodiment of a popping toy in accordance with the present invention;

FIG. 9 is a top view thereof;

FIG. 10 is a bottom view thereof;

FIG. 11 is a front view thereof;

FIG. 12 is a back view thereof;

FIG. 13 is a left view thereof;

FIG. 14 is a right view thereof;

FIG. 15 is a front, top perspective view of another embodiment of a popping toy in accordance with the present invention;

FIG. 16 is a top view thereof;

FIG. 17 is a bottom view thereof;

FIG. 18 is a front view thereof;

FIG. 19 is a back view thereof;

FIG. 20 is a left view thereof; and,

FIG. 21 is a right view thereof.

The broken lines showing the remainder of the popping toy are directed to environment. In FIGS. 1 and 2 the broken lines immediately adjacent to the outer perimeter of the stippled area represent the bounds of the claimed design while all other broken lines are directed to environment and are for illustrative purposes only. In FIGS. 8 and 9 the broken lines immediately adjacent to the inner perimeter of the stippled area represent the bounds of the claimed design while all other broken lines are directed to environment and are for illustrative purposes only. None of the broken lines form any part of the claimed design.

1 Claim, 9 Drawing Sheets
